CLAIM

The ornamental design for a light emitting diode (LED) package, as shown and described.

DESCRIPTION

FIG. 1 is a top perspective view of a light emitting diode (LED) package showing our design according to one embodiment;

FIG. 2 is a bottom perspective view thereof, opposite the view of FIG. 1;

FIG. 3 is a top plan view thereof;

FIG. 4 is a bottom plan view thereof, opposite the view of FIG. 3;

FIG. 5 is a first side view thereof;

FIG. 6 is a second side view thereof, opposite the view of FIG. 5;

FIG. 7 is a third side view thereof;

FIG. 8 is a fourth side view thereof, opposite the view of FIG. 7;

FIG. 9 is a top perspective view of a light emitting diode (LED) package showing our design according to a second embodiment;

FIG. 10 is a bottom perspective view thereof, opposite the view of FIG. 9;

FIG. 11 is a top plan view thereof;

FIG. 12 is a bottom plan view thereof, opposite the view of FIG. 11;

FIG. 13 is a first side view thereof;

FIG. 14 is a second side view thereof, opposite the view of FIG. 13;

FIG. 15 is a third side view thereof;

FIG. 16 is a fourth side view thereof, opposite the view of FIG. 15;

FIG. 17 is a top perspective view of a light emitting diode (LED) package showing our design according to a third embodiment;

FIG. 18 is a bottom perspective view thereof, opposite the view of FIG. 17;

FIG. 19 is a top plan view thereof;

FIG. 20 is a bottom plan view thereof, opposite the view of FIG. 19;

FIG. 21 is a first side view thereof;

FIG. 22 is a second side view thereof, opposite the view of FIG. 21;

FIG. 23 is a third side view thereof;

FIG. 24 is a fourth side view thereof, opposite the view of FIG. 23;

FIG. 25 is a top perspective view of a light emitting diode (LED) package showing our design according to a fourth embodiment;

FIG. 26 is a bottom perspective view thereof, opposite the view of FIG. 25;

FIG. 27 is a top plan view thereof;

FIG. 28 is a bottom plan view thereof, opposite the view of FIG. 27;

FIG. 29 is a first side view thereof;

FIG. 30 is a second side view thereof, opposite the view of FIG. 29;

FIG. 31 is a third side view thereof; and,

FIG. 32 is a fourth side view thereof, opposite the view of FIG. 31.

The uniformly broken lines are for illustrative purposes only and form no part of the claimed design.

The dot-dash-dot broken lines (e.g., in FIG. 17) represent boundaries of the claimed design and form no part of the claimed design.
